(57) **CLAIM**

The ornamental design for a cable handle and holder assembly as shown and described.

DESCRIPTION

FIG. 1 is a front elevation view of a cable handle and holder assembly, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof; and,

FIG. 8 is a rear perspective view thereof, in an alternate configuration.

The broken lines in the drawings (short dash-short dash broken lines) illustrate portions of the cable handle and holder assembly that form no part of the claimed design. The cable handle and holder assembly is shown with a symbolic break in its length. The appearance of any portion of the article beyond the break line forms no part of the claimed design.

The long dash-long dash broken lines in the drawings illustrate stitching of the cable handle and holder assembly that forms a part of the claimed design.
